UNITED STATES PATENT OFFICE.

NOAL W. SPENCER, OF SIOUX FALLS, SOUTH DAKOTA.

INCLINOMETER FOR AEROPLANES.

1,399,090.

Specification of Letters Patent. Patented Dec. 6, 1921.

Application filed August 13, 1920. Serial No. 403,349.

To all whom it may concern:

Be it known that I, NOAL W. SPENCER, a citizen of the United States, residing at Sioux Falls, in the county of Minnehaha 5 and State of South Dakota, have invented certain new and useful Improvements in Inclinometers for Aeroplanes, of which the following is a specification.

This invention relates to certain new and 10 useful improvements in an inclinometer for aeroplanes, the principal object being to provide a simple and reliable device for indicating whether or not the aeroplane is flying upright or otherwise. In cloudy or foggy 15 weather the pilot experiences difficulty in ascertaining whether the aerial machine is upright, tilted, or even upside down, and because of the pilot's inability to determine his position accidents and uneven wear on the 20 motor pistons, and other moving parts, occur which it is the aim of the present invention to obviate.

The invention therefore consists in the features of construction, and the arrangements and combinations of parts hereinafter 25 described and claimed, reference being made to the accompanying drawings wherein:

Figure 1 is a front elevation of the improved inclinometer; 30 Fig. 2 is a vertical, transverse section therethrough on line 2—2 of Fig. 1;

Fig. 3 is a view similar to Fig. 1, with portions removed; and

Fig. 4 is a top view thereof.

The body 1 is suitably supported on a base 2 and is supplemented by front section or face plate 3 in forming therewith a sectional casing or housing for the indicator devices. Both sections are substantially 35 identical above the base 2, consisting of dished shell structures having central, registering openings 4 and concentric segmental, registering slots 5 thereover, said openings and slots constituting sight openings 40 for viewing the indicators hereinafter described. The two sections are secured together along their upper edges by the lug 6 engaging in slot 7 and at their lower edges by screws 8.

Supported within the central openings is a globular or spherical glass container 9 having a filling neck 10 depending between the casing sections and being closed by a stopper 11. This container is partly filled 55 with a non-freezing liquid 12, in which floats an indicator 13 preferably hollow and

weighted by a small quantity of mercury 14. This construction presents, on each side, a spheroidal segment clearly open to view with a free space above the liquid content 60 through which the upper end of the indicator projects. In fact the indicator can also be viewed through the liquid, the latter serving as a lens for enlarging the same to the eye. An arcuate dial 15 is interposed 65 between the sight openings of the face plate to facilitate the reading of the angle of inclination of the machine, the lower portion of the face plate providing a suitable mounting for a thermometer 16.

An arcuate tube 17 is located in the slots 5 and contains a liquid providing a level air bubble 18 for further determining the inclination of the machine.

In assembling the parts the two indicators 75 are arranged in the sight openings of the body 1 and the surrounding space filled with plaster Paris, or other cement 19 after which the face plate is secured in position. The lower portion of the casing forms a chamber 80 20 through which the stopper 11 is accessible.

The construction is simple and easily read from either side, the central indicator having a free, floating and universal mounting 85 whereby it is operable in all directions.

Obviously if the indicator 13 is not diametrically disposed at the time of reading, an imaginary diametral line parallel with the indicator will readily aid in determining 90 the degree marking on the dial.

What is claimed is:

1. An inclinometer for aeroplanes, comprising a casing consisting of supplemental sections having registering central and relative concentric sight openings, an arcuate bubble indicator disposed in the concentric sight openings, a second indicator engaged in the central sight openings and an arcuate dial between and common to both indicators. 95

2. An inclinometer for aeroplanes, comprising a sectional casing, said sections having registering sight openings, a spherical, transparent container of greater diameter than that of the openings engaged in the 100 openings, so as to be held by the sections and to project outwardly from the latter, a liquid in the container, and an indicator floated within the container.

3. In an aeroplane inclinometer, a pair of 110 plates having registering central openings and registering concentric segmental slots

- above the openings, a spherical glass container having a liquid therein arranged in the central openings, an arcuate tube having a liquid containing a bubble therein and arranged in the slots, an arcuate dial between the spherical container and the tube, and an indicator in the container, the tube and container extending outwardly beyond the sides of the plates.
10. 4. An inclinometer for aeroplanes, comprising a sectional casing, said sections having registering sight openings, a spherical, transparent container engaged in the casing openings, said container having a filling neck depending between the casing sections and normally closed, a liquid within the container, an indicator within the container floated by the liquid, a second indicator concentrically arranged about the first indicator and a cementitious filler in the casing between the container and second indicator and above the latter for securing the container and second indicator in position.
5. An inclinometer for aeroplanes, comprising a sectional casing having openings, a plurality of indicator means clamped in position by the edges defining the openings of the sections of said casing, and means removably holding the sections together.
30. 6. In an aeroplane inclinometer, a pair of spaced plates having central registering openings and registering curved slots, indicator means including a globular member arranged in the openings and a second indicator means including an arcuate member arranged in the slots, the indicators being of greater diameter than the diameter and widths of the slots respectively so as to be

held by and between the plates and to project outwardly beyond the latter.

7. In an aeroplane inclinometer, a pair of spaced plates having central registering openings and registering curved slots, indicator means including a globular member arranged in the openings and a second indicator means including an arcuate member arranged in the slots, the indicator members being of greater diameter than the diameter and widths of the slots respectively so as to be held by and between the plates and to project outwardly beyond the latter and a cementitious filler in the casing between the indicator members and between the upper indicator member and the tops of the plates.

8. In an aeroplane inclinometer, a hollow spherical container having a liquid therein, an elongated indicator in the container weighted at its lower end and freely floating in the liquid and having its outer end extending above the liquid, and a curved member arranged above the container and having its ends terminating in spaced relation to each other and arranged on opposite sides of the container so that upon reversal of the container the outer end of the indicator will be disposed in a plane between the ends of the curved member.

9. In an aeroplane inclinometer, a pair of spaced plates having central registering openings, and indicator means including a globular member of greater diameter than said openings arranged in the openings to project outwardly from the plates.

In testimony whereof I affix my signature.

NOAL W. SPENCER.
